UNITED STATES PATENT OFFICE.

JOSEPH M. BARRETT, OF BOSTON, MASS., OHIO.

FEED-WATER REGULATOR.

Application filed October 22, 1926. Serial No. 142,337.

This invention relates to fluid pressure generators of the type particularly adapted to function with the boilers carrying high pressure, and is concerned with certain improvements over the existing types of generator, which have been found inadequate and incapable of meeting demands resulting from high pressure practice.

The general principle of a fluid pressure generator is disclosed in the patent to Copley 1,193,125 issued August 3rd, 1916. This device comprises two chambers, one of the chambers comprises part of a conduit which spans the normal water level of a boiler. The second chamber encompasses the first and is positioned in an extension of the plane of the water level so that when the water lowers, steam enters the first chamber and heats the contents of the second chamber. The second chamber contains a volatile fluid which is heated by the steam in the first chamber and the rate of heating is proportional to the ratio of water to steam in the first chamber, due regard being had for the temperature and heat content of the water and steam. The fluid in the second chamber upon being heated tends to volatilize and expand so that a pressure is created which may be transmitted to pressure actuatable means. For the purpose of illustration I show the pressure actuatable means as being a diaphragm actuated feed water valve, and the particular use, the regulating of feed water to a high pressure boiler.

Copley conceived his invention more than 12 years ago and the problem with which he was then confronted was vastly different from that which now confronts me. As one who is skilled in the art can appreciate changes have taken place in boiler design and power plant structure that have been so vast that installations which were considered then modern are now regarded as relatively inefficient or nearly obsolete. The most acute point in a change of boiler design has been in the increase in pressure. Where in Copley's day a pressure of two hundred to two hundred and fifty pounds was considered very high, we find today boiler pressures of six to seven hundred pounds to be common; a pressure of twelve hundred pounds actually in use, and pressures of fifteen hundred to two thousand pounds to be expected in the near future. I need not go into the causes for the use of high pressure, but I am concerned with the

effect of the use of high pressure on the auxiliary equipment particularly on the action of pressure generators and the regulation of feed water. The increase in steam pressure has resulted in smaller boiler sections and thicker boiler drum walls which along with the increase in rating has greatly reduced the quantity of water in the boiler and in the drum and this reduction has taken place while the rate of evaporation has enormously increased. The result is then that the feed water velocity and the steam velocity are very high; that the tendency for change in water level is very great and the danger resulting from such a change is not only more imminent but more real.

It is therefore among the objects of my invention to so construct a pressure generator unit that the generator will be quickly responsive to changes of water level in a boiler carrying steam at high pressure and temperature; that the generator may have a capacity large enough to provide a substantial volume of fluid under pressure to operate the diaphragm valve where the valve moves in a stream of high pressure and high velocity, and that the generator unit may accurately function without regard to the formation of hot condensate and that other factors which disturb the temperature differential of the heat input.

In the drawings Figs. 1, 2, 3 and 4 are diagrammatic illustrations of positions and conditions, descriptive of the use of the generator; Fig. 5 is an elevation of an installation including the pressure generator and the conduit which is adapted to the boiler drum; Fig. 6 is a partial section taken along the line 6-6 of Fig. 5; Fig. 7 is a section taken along the line 7-7 of Fig. 6 and Fig. 8 is a layout of an apparatus constituting a feed water regulating device for a boiler.

Before describing the apparatus embodying my invention I wish to point to the diagrams, Figs. 1, 2, 3 and 4 to show the action which takes place in a pressure generator of the general type employed in my invention. Referring to Fig. 1, I show the generator chamber G containing a working fluid WF surrounding the conduit C (which is connected to the boiler drum) containing hot steam S above the water level indicated L. The lower portion of the conduit C within the chamber G contains water W. The speed of response of the generator is a function of the difference in temperature and

heat between the stem and the water which acts upon the working fluid. Thus, if the difference in temperature is great, the action will be rapid, and if the difference in temperature is slight, the action of the generator will be sluggish. The water W is cooled by conduction through the working fluid and through radiating fins (see Fig. 6), but the temperature of the water W is increased first by the conduction of heat from the steam S along the walls of the conduit C ; second, by the direct transfer of heat from the steam S across the water surface; thirdly the condensation of steam in the conduit C flowing down and becoming part of the water; and fourthly, the surging or mixing of the steam and water due to more or less rapid changes in water level. The angular disposition of the generator relative to the water level is seen to change the size of the area of the water level indicated A^1 . Thus in Fig. 2, the area A^1 is much greater than the area shown in Fig. 1 and the temperature of the water in the generator is proportionally higher by reason of the transfer of heat at the surface, the transfer due to the surge effect or mixture of the water and the steam, and the temperature of the water W is increased because a greater area of the conduit C is heated which is common to both water and steam. It will be seen, therefore, that a generator angularly disposed near the horizontal will have a sluggish and ineffectual action.

In the solution of my problem therefore, it is found advisable except for the accumulation of condensate, to dispose a generator more nearly the vertical as shown in Fig. 1. With the generators disposed more nearly the vertical and for a given size of the conduit C for an ample quantity of working fluid, a comparatively smaller steam heating surface is exposed for a given change in water level. I might compensate for this to a certain extent by increasing the diameter of the conduit C , but I find it more advantageous to use a plurality of conduits C as shown in Figs. 3 and 4 so that a greater heating surface per cubic inch of steam is provided. For convenience of manufacture and for reasons which will presently appear, I find that a plurality of conduits and chambers as shown in Fig. 4 make possible a better balance between interior heat input and exterior radiation.

In Fig. 5 I designate the conduit 1 which is adapted to be connected through the valves 2 and 3 and suitable fittings into a boiler drum. The conduit 1 is formed to include a depending looped portion which permits expansion and contraction and provides a cold water leg or reservoir. The generator may be connected into the conduit with suitable high pressure joints 4 and 5. The generator unit (see Fig. 6) comprises a

conduit 10 disposed between the joints 4 and 5 to communicate directly with the upper and lower portions of the conduit 1. Branching from the conduit 10 at the points 11 and 12 respectively are the branch conduits 15 and 16. On each of the conduits 15 and 16 and enclosing the upper portions thereof are mounted the generator casings 17 and 18. One of these generators may advantageously extend to a higher elevation than the other so that the higher one may generate an initial pressure for both generators. I show each of the casings as having expansible heads on both the upper and lower ends. These heads may be brazed onto the conduits 15 and 16 respectively, or may be otherwise joined by suitable means. Each casing constitutes a cylindrical portion lying concentric with the conduits 15 and 16 and spaced therefrom to provide a chamber in which the expansible fluid is stored. On the exterior of the cylindrical portion of the casing I mount suitable radiating fins 19 and 20. The number and the nature of the radiating fins is a factor which must be balanced against the heat input or rather the rate of heat input into the generator. In each of the casing members and preferably adjacent the uppermost point as shown, I provide filling plugs 25 and 26. The filler plugs 25 and 26 may be vertically displaced relative to each other. Both plugs are removed when the generator system is filled so that the smaller chamber will then be full but in the larger chamber there will be an air pocket. I find that this air pocket provides what I am pleased to call a tempering or cushioning effect on the action of the generator and the pressure responsive means. By using the two generator units and placing them as I do, I am assured that the operator using my invention will naturally provide this air pocket when he fills the generator. Joining the two casings and near the lower ends I show the conduit 30 which provides communication from one chamber to another. The conduit 30 may be curved (see Fig. 7) to allow for expansion and contraction. Tapped into the lower portion of one of the casings I show a conduit 31 (see also Figs. 6, 7 and 8) which is adapted to lead to the pressure responsive device actuated by the pressure generated in the chambers 17 and 18 (Fig. 8).

Referring back to Fig. 6 it will be seen that a substantial portion of the branch conduits 15 and 16 is provided between the generators and the point of juncture 12. In contrast with the length of the portions of the branch conduits 15 and 16 which are between the joint 12 and the lower portions of the generators, I show the upper portion of the branch conduit between the joint 11 and the upper portion of the generator as being

relatively short. The lower inner surface of each of these portions of the branches 15 and 16 between the joint 11 and the points A, 5 may slant downwardly slightly in the direction of the joint 11. I have found this slanting advantageous, but I do not care to be specifically limited to this construction. The slant may be formed by slightly flattening or tipping this portion of the branch 10 conduits. A slight slope permits any condensate which forms in the upper portion of the branch to drain back into the conduit 10 rather than into the longitudinally extending portion of the branches. Thus I design- 15 ate the vertically extending portion of the branch conduits above the tops of the generators as the portions B and B'. It will be seen that only condensate forming in the portions B and B' will drain into the generator. The amount of condensate will be so 20 small and the heat contained therein will be negligible compared to the radiating ability of the generator. By positioning the generators on the branch conduits, it will be seen 25 that I have reduced the length of pipe in which condensate may form from that be- 30 tween the point 40 which is at water level up to and including the valve and the fittings at the boiler drum, to the comparatively short portion, to wit, the portions B and B' 35 over the respective generator chambers. The portions of the branches 15 and 16 between the tops of the generators and the joint 11 may be advantageously covered with insulating 40 material, as I have shown, for illustration at I.

As mentioned above the condensate forming between the points A and the joint 11 will flow back into the conduit 10 and also 45 the condensate forming between the valve and joint 2 down to the point 40 will accumulate in the conduit 10. It will be seen that the generators themselves are practically free from the harmful effect of the collection of condensate. Conversely, the lower 50 portion of the conduit 10, or that portion above the joint 12, contains water which has had substantial opportunity to cool and it will be further seen that the water in the branches 15 and 16 may be maintained so cold that whenever the water level rises the water forced up into each of the generators will chill the generator and cause a rapid negative movement of the pressure actuatable 55 means.

I am able by using my generator unit, even without insulating means around the upper portion of the conduit 1 and the upper portions of the conduits 15 and 16 to effect excellent regulation of high pressure boilers. The amount of condensation forming and actually getting within the confines of the pressure generators is only a small fraction of that condensate continually forming and 60 collecting at the point 40 in the conduit 10.

The collection of condensate at the point 40 causes a continuous downward flow of water through the conduit 10 along the lower leg of the conduit 1 and back into the boiler at the point 3. The temperature of this water 70 varies from point to point along its path and depends upon the rate of condensation. Whatever the temperature of that body of water might be, it will be seen, that the rate of flow of water in the conduits 15 and 16 75 downwardly is only proportional to the rate of accumulation of condensate in the branch conduit. This rate is only a bare fraction of the rate of collection of condensate in the main conduit so that the rate of flow of water 80 due to condensation in the conduits 15 and 16 is practically nil.

My invention therefore provides a very sensitive apparatus because of the great temperature differential between the water and steam in contact with the generating chamber. My invention is particularly well adapted for use in connection with boilers wherein the steam is very hot and the feed water velocity very high.

I claim:

1. In a pressure generator unit adapted to be active in response to a difference in temperature between water and steam, the combination of means for conducting to said pressure generator water and steam, and means for by-passing the water of condensation from the steam in said first named means away from the pressure generator so that the temperature differential between the water and steam in contact with the pressure generator is not decreased by the heat of the condensate.

2. The combination of a boiler drum containing water and steam, a conduit connected to the boiler drum and disposed exteriorly of said drum and spanning the water level thereof, pressure generator means responsive to the temperature differential between water and steam in contact therewith, a branch conduit associated with the main conduit and joined thereto at points above and below the water level and adapted to carry said pressure generator means whereby the water of condensation in the first conduit will accumulate and circulate without the branch conduit and away from said pressure generator means.

3. The combination of a boiler drum containing water and steam, a conduit connected to the drum and spanning the water level thereof, thermo-responsive means associated with said conduit at the water level, a branch conduit associated with the main conduit and adapted to carry said thermo-responsive means whereby the water of condensation formed in the first conduit will circulate without the branch conduit and out of contact with said thermo-responsive means.

4. In a fluid pressure generator system,

- the combination of a boiler drum containing water and steam, a conduit adapted to span the water level in said drum and connected thereto and forming a closed loop exteriorly of the drum from the steam space to the water space, a branch conduit leading from said first named conduit at a point above the water level and joined again thereto at a point substantially below the water level, a fluid pressure generating chamber responsive to the temperature differential of the fluids in the conduit and associated with the branch conduit along the upper portion thereof and intercepting the plane of the water level, whereby the condensate formed in the first named conduit circulates in the first conduit independently of the branch conduit and the said generating chamber is not heated by the condensate.
5. In a fluid pressure generator system, the combination of a boiler drum containing water and steam, a conduit adapted to span the water level in said drum and connected thereto and forming a closed loop exteriorly thereof, a branch conduit leading from said first named conduit at a point above the water level and lying parallel to said first named conduit and joined again thereto at a point substantially below the water level, a fluid pressure generating chamber associated with the branch conduit and intercepting the plane of the water level whereby the condensate formed in the first named conduit circulates therein independently of the branch conduit and the said chamber is not heated by the condensate.
6. The combination with a boiler drum containing water and steam of a conduit disposed exteriorly of said drum communicating with the steam and water spaces thereof, said conduit containing water flowing toward the water space in the boiler by reason of the condensation of steam in the conduit, a branch conduit joined to said first named conduit at a point but slightly above the water level and joined at another point below the water level, pressure generator means responsive to the temperature differential of the fluid in said branch conduit and associated with said branch conduit and positioned along the upper portion thereof, the portion of the branch conduit above the generator containing steam being short and the portion of the branch conduit below the generator comprising an auxiliary cold water leg whereby the heat input into the generator may be sharply defined by the hot steam and cool water in the said branch conduit to the exclusion of the condensate in the main conduit.
7. The combination with a boiler drum containing water and steam, of a conduit disposed exteriorly of said drum and communicating with the steam and water spaces thereof, said conduit containing water flowing toward the water space in the boiler by reason of the condensation of steam in the conduit, a branch conduit joined to said first named conduit at a point above the water level and joined at another point below the water level, thermo-responsive means associated with said branch conduit and positioned on the upper portion thereof, part of the portion of the branch conduit above the generator containing steam being adapted to drain into the first conduit whereby the heat input into the thermo-responsive means may be sharply defined by the temperature differential between the steam and water in the said branch conduit to the exclusion of the condensate in the main conduit and the said part of the upper portion of the branch conduit.
8. In a pressure generator unit containing an expansible fluid and adapted to be actuated in response to the difference in temperature between water and steam in contact therewith, the combination of means for conducting to said pressure generator water and steam, means for by-passing the water of condensation away from the pressure generator unit and means for dissipating the heat of the expansible fluid, so that the water in contact with the pressure generator may be greatly cooler than the steam in contact therewith.
9. The combination of a container partially filled with hot steam, a conduit connected to span the water level of the container and containing steam and water flowing downwardly in the conduit by reason of the condensation of steam therein, a branch conduit joined to the first conduit at points above and below the water level, thermal responsive means associated with the branch conduit and responsive to the temperature differential of the fluid therein, the portion of the branch conduit containing steam being short so that the flow of fluid in the branch conduit due to condensation is slight whereby a substantial temperature differential of the fluid adjacent the said thermo-responsive means is maintained.
10. In a fluid pressure generator system, the combination of a boiler drum containing water and steam, a conduit communicating with the steam space and the water space of said drum, means including a by-pass for connecting said conduit with said drum, said means containing water and steam in which water flows into the boiler by reason of the condensation of steam above the water level therein, said conduit having a short portion filled with steam and a relatively long portion filled with water so that the flow of water in said conduit due to the condensation of steam therein is very slow compared to the movement of water in said means and by-pass, a chamber associated with said conduit and disposed near the upper portion

thereof and lying concentrically therewith and containing a fluid adapted to be expanded by an increase in temperature or heat content of the fluid within the conduit and 5 heat radiating means disposed exteriorly of said chamber whereby the temperature of the fluid therein is maintained low except in response to the contact with steam in the branch conduit.

10 11. The combination with a container containing water and steam, a conduit communicating with the steam and water spaces thereof, said conduit containing water flowing toward the water space in the container 15 by reason of the condensation of steam in the conduit, a branch conduit joined to said first named conduit at a point, but slightly above the water level, thermoresponsive means responsive to the temperature differential of the fluid in said branch conduit and associated with said branch conduit, the portion of the branch conduit above the said thermoresponsive means being short and the portion of the branch conduit below the 20 thermoresponsive means comprising a cold water leg, whereby the heat input into the thermoresponsive means may be sharply defined by the hot steam and relatively cool water in said branch conduit to the exclusion 25 of the condensate in the main conduit.

30 12. The combination of a container for water and steam, a conduit connected with the container and spanning the water level thereof, a branch conduit joined to the first 35 named conduit at a point above the water level in said conduit, thermoresponsive means associated with said branch conduit, whereby water of condensation formed in the said first named conduit circulates independently 40 of the branch conduit.

45 13. The combination of a container for water and steam, tubular conducting means spanning the water level and comprising a plurality of conduits joined to have a common portion above the water level, thermoresponsive means associated with said tubular conducting means at the water level, one 50 of the said plurality of conduits being disassociated from the said thermoresponsive means and comprising a by-pass for condensate.

55 14. The combination of a container for water and steam, a conduit connected with the container and spanning the water level thereof, two branch conduits joined to the first named conduit at a point above the water level in said conduit, thermoresponsive means associated with each of said branch conduits at substantially the point of normal water level in the container, the effective elevation of one of said thermoresponsive means being higher than that of the other.

60 15. The combination of a container for water and steam, a conduit connected with

the container and spanning the water level thereof, two branch conduits joined to the first named conduit at a point above the water level in said conduit, thermoresponsive devices comprising closed chambers 70 surrounding an inner conduit and having an expansible fluid therein, said chambers being connected together and each associated with one of said branch conduits at substantially the point of normal water level in the 75 container, the effective elevation of one of said chambers being higher than that of the other whereby the higher device delivers an initial pressure in both devices when the steam descends to its upper portion and whereby 80 both devices act together as the steam continues to descend in both of them.

16. The combination of a container for water and steam, a conduit connected with the container and spanning the water level 85 thereof, two branch conduits joined to the first named conduit at a point above the water level in said conduit so that condensate may circulate in the first conduit independently of the branch conduits, thermoresponsive means associated with each of said branch conduits at substantially the normal water level, and fluid conducting means connecting said thermoresponsive means together whereby they act conjointly. 90

17. The combination of a container for water and steam, a conduit connected with the container and spanning the water level thereof, a plurality of branch conduits joined to the first named conduit above the water level in said conduit, thermoresponsive means associated with each of said branch conduits whereby water of condensation formed in said first named conduit circulates independently of the branch conduits, 100 said thermoresponsive means being connected together so that uniform pressure may be maintained therein, one of said thermoresponsive means being disposed with its upper portion at a higher elevation than any other and having an air pocket in the uppermost portion thereof, whereby a cushioning or tempering effect for all the thermoresponsive means is provided by the air 110 pocket in one. 115

18. The combination of a container for water and steam, a plurality of conduits connected with the container and spanning the water level thereof, thermoresponsive means each associated with one of said conduits in the plane of the water level, said thermoresponsive means being connected together so that uniform pressure may be maintained therein, one of said thermoresponsive means being disposed with its upper portion at a higher elevation than the other and having an air pocket in the upper portion thereof, whereby a cushioning or tempering effect is obtained by the air there- 120 in. 125

19. The combination of a container for water and steam, a plurality of conduits spanning the water level thereof and inclined more nearly the vertical than horizontal at the water level, thermoresponsive devices each comprising a closed chamber containing expansible fluid and each surrounding one of said conduits at the water level, and fluid conducting means affording communication between said chambers for maintaining uniform pressure therein.

20. The combination of a container for water and steam, a thermoresponsive unit including a plurality of parallel conduits all lying in a plane inclined nearer the vertical than the horizontal, each conduit being enclosed by a closed chamber at the level of water in the container, the several chambers being interconnected and having fluid com-

munication with each other, and means connecting said unit with the steam and water spaces of the container from points above and below said unit respectively.

21. A container for water and steam, a plurality of conduits spanning the water level and communicating with the steam and water spaces of said container, thermoresponsive means associated with each conduit at the water level and extending to different elevations above the water level, said thermoresponsive means being inclined more nearly the vertical than the horizontal and means connecting the thermoresponsive means together whereby they act conjointly.

In testimony whereof, I hereunto affix my signature.

JOSEPH M. BARRETT.
